SOLDERING IRON STAND

Roy J. Denny, Jr., Overland, and Charles H. Mudd,
St. Louis, Mo.

Application September 22, 1958, Serial No. 52,718

Term of patent 14 years

(Cl. D54—1)

FIG.1.

FIG.2.

FIG.3.

FIG.4.

Fig. 1 is a top plan view of the soldering iron stand embodying our new design;

Fig. 2 is an end elevational view of the same;

Fig. 3 is a side elevation of the same, depicting the side from which the soldering iron is inserted into the stand, and

Fig. 4 is a side elevation of the same, depicting the opposite side of the stand.

We claim:

The ornamental design for a soldering iron stand, as shown and described.
